UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

DRAFT RIGGING.

Application filed November 13, 1922. Serial No. 600,660.

To all whom it may concern:

Be it known that I, DONALD S. BARROWS, a citizen of the United States, residing at Rochester, in the county of Monroe and State of New York, have invented certain new and useful Improvements in Draft Rigging; and I do hereby declare the following to be a full, clear, and exact description of the invention, such as will enable others skilled in the art to which it appertains to make and use the same.

My invention relates to draft rigging back stops such as are used between the center sills or draft sills of a railway car for the purpose of transmitting to the car underframe buffing shocks to which the draft rigging mechanism is subjected under service conditions.

The principal feature of the invention, generally stated, is to provide a back stop casting having its end or buffing wall, the reinforcing portions therefor, and other webs and flanges arranged and disposed so as to economically distribute the metal and produce a casting of maximum strength value but comparatively light in weight.

Particularly stated, the invention has for an object the provision of a back stop casting having a reinforced front face or buffing wall formed by diverging webs or flanges arranged transversely of the casting, said webs uniting the side walls and forming a hollow chamber or column portion between the spaced car sills to which latter the casting is connected.

The invention further involves the production of a back stop casting in which the buffing wall is adequately braced at a plurality of spaced points by means of transversely disposed webs which provide a triangular reinforcement adjacent the buffing wall.

Another object of the invention is to provide a combined back stop and center filler casting which may be effectively used with car underframes of different types, said casting being provided with a reinforced buffing wall and a plurality of webs or flanges advantageously arranged about the center thimble to receive and distribute without distortion the enormous shocks or blows to which the casting is subjected in actual service.

A further object of the invention resides in the provision of a back stop member

adapted to be connected to the car sills and arranged to cooperate with a movable element of the draft rigging, said back stop member being formed with maximum and readily accessible riveting areas at the most advantageous points for attaching the back stop to the car underframe.

With these and other objects in view, the invention further consists in the combination and arrangement of the parts all as will hereinafter appear.

In the drawings illustrating the invention, the scope whereof is pointed out in the claims:

Figure 1 is a plan view of a back stop embodying the invention showing its assembled relation to a portion of the car underframe and to a part of the draft rigging mechanism.

Figure 2 is a vertical longitudinal sectional view on the line 2—2 of Figure 1.

Figure 3 is a vertical transverse sectional view through the back stop casting on the line 3—3 of Figure 2.

Figure 4 is a plan view partly in section of a modified form of back stop embodying my invention.

Figure 5 is a vertical longitudinal sectional view on the line 5—5 of Figure 4.

Figure 6 is a rear view in elevation of the modified form of back stop shown in Figures 4 and 5.

Figure 7 is a vertical transverse sectional view on the line 7—7 of Figure 5 of the modified form of back stop.

Figure 8 is a top plan view of still another form of modified construction embodying the invention, a part thereof being shown in section.

Figure 9 is a vertical longitudinal sectional view on the line 9—9 of Figure 8.

Figure 10 is a rear view in elevation of the modified form of back stop shown in Figures 8 and 9.

Referring to the drawings in which similar reference characters designate corresponding parts, the draft rigging 1 with which the back stop cooperates and spaced car sills 2 between and to which the back stop is secured, may be of any suitable form. In the well known type of draft rigging, a portion of which is illustrated in the drawings, the rear end of the draft yoke 3 is the movable part of the draft rigging which is adapted to communicate buffing

shocks to the back stop. It is to be understood that this special form of draft rigging is merely illustrative and is not disclosed for the purpose of limiting the invention 5 to use in conjunction therewith.

My invention, as embodied in the form of back stop shown in Figures 1, 2 and 3, includes longitudinally extending side walls 4 each of which is provided with a plurality 10 of rows of openings adapted to receive the connecting rivets 5, whereby the structure may be firmly connected to the sills 2 of the car underframe. Each of the side walls 4 is provided along its upper edge with relatively 15 high portions or projections 6, said projecting portions being disposed forwardly and rearwardly of the center thimble 7 and arranged to provide an increased riveting area through which the uppermost row 20 of rivets pass. A portion of each side wall is cut away, as indicated at 8, between the projecting portions 6, thereby reducing the relative weight of the casting but effectively maintaining a sufficient riveting area at the 25 most advantageous points.

The side walls 4 are preferably united at their front ends by means of an upright 9 transversely extending front end wall 9 adapted to form an abutment for the movable element or yoke 3 of the draft rigging. The front end wall 9 is also united to the side walls 4 by means of the diverging webs 10 transversely disposed immediately in the rear of said front end wall and arranged to 30 provide a triangular reinforcement. One of the reinforcing webs 10 is united with the front wall relatively near the uppermost portion thereof, and the other of said webs is united with the front wall near the lowest portion thereof, both of said webs being united to each other in spaced relation from said end wall, thereby forming a hollow column or chambered portion extending transversely of the casting immediately adjacent the rear of the buffing or front end wall 9. The hollow column or chambered portion is preferably designed to extend transversely through the back stop casting, said hollow column or chambered portion 40 opening directly against the car sills to which the side walls of the casting are connected. This type of hollow column reinforcement provides a particularly effective construction which can be easily cast.

United to the diverging webs 10 at their juncture in the rear of the front wall, is a longitudinally disposed substantially horizontal web 11, said web 11 being designed to unite the side walls 4 and also connected to the center thimble 7. Openings 12 are provided in the horizontal web 11 preferably adjacent the side walls thereof, said openings permitting access to the base or floor web 13 and more particularly the rivets 14 45 which secure the casting to the bolster center

plate. The openings 12 are preferably arranged in vertical alignment with the portion of the floor web 13 through which the attaching rivets 14 extend. Bracing webs 15 serve to unite the side walls with the horizontal web 11, said bracing webs extending beneath the horizontal web and united with the floor web or base portion 13 of the casting transversely thereof, as best shown in Figure 3. A transversely disposed upright web 16 unites the center thimble on opposite sides thereof with the side walls, said web 16 being disposed at the inner edge of the horizontal web 11.

A longitudinally disposed centrally located upright web 17 extends rearwardly from the front end wall 9, said upright web being united to the diverging webs 10 and the horizontally disposed web 11. The vertical web 17 extends above and below the horizontal web 13, portions of said upright web being connected to the base portion or floor web 13, and other portions of said upright web being united to the center thimble. The casting may be further braced at 80 its rear portion by longitudinally extending ribs 18, said ribs being intersected by transversely disposed vertical ribs 19, both of said ribs 18 and 19 being united to the side walls, as shown. The ribs 19 project beneath the horizontal ribs 18 and are united with the floor web 13 of the casting transversely thereof, forming in effect the rear wall of said casting. A rear bracing rib 20 may be provided longitudinally of the casting, said bracing rib uniting the base portion or floor web of the casting and the center thimble. 95

In Figures 4 to 10 inclusive, I have shown two modifications of my invention adapted for use with car underframes of different types. These are but some of the various adaptations of my present invention which in the forms shown herein involve a casting composed of spaced side walls, a rear wall, and a front end or buffing web, suitably braced or reinforced to resist the heavy strains incident to service conditions.

The form of back stop casting shown in Figures 4 to 7, inclusive, includes side walls 21 united at their forward ends by a transversely disposed upright web 22, which web forms the buffing abutment of the casting. Diverging rearwardly from the buffing wall 22 are bracing webs 23, said webs being transversely arranged adjacent the rear face of said buffing wall and united in spaced relation therefrom to form a hollow column reinforcement of triangular contour. A longitudinally extending horizontal web 24 is united with the diverging webs 23 at their points of juncture, the lowermost of said webs 23 being united with the horizontal web slightly in the rear of the junction of the uppermost web 23 with said horizontal web 24. This relatively offset junction of 110

the respective diverging webs 23 and the forward end of the horizontal web 24 is clearly shown in Figure 5. The horizontal web extends longitudinally through the casting to the rear wall 25 thereof and is preferably inclined upwardly toward the longitudinal center of the casting, as shown in Figures 6 and 7. A vertical longitudinally extending web 26 intersects the horizontal web 24 and also is united with the respective diverging webs 23 and the front end wall 22. The lower edge of the vertical or upright web 26 is united with the base or floor web 27 of the casting.

15 The modification shown in Figures 8, 9 and 10 includes a casting formed with side walls 28 united at their forward ends by an upright buffing or front end wall 29. The front end wall is reinforced by transversely disposed divergent webs 30, said webs uniting the side walls and front walls, and also being united to each other at the rear of the front end wall to form the triangular reinforcement best shown in Figure 9. From the junction of the webs 30 extends a horizontal web 31, said web serving to unite the bracing webs 30 with the rear wall 32, and also transversely connecting the side walls of the casting. A central longitudinally extending upright web 33 intersects the horizontal web 31 and serves to unite the front and rear walls of the casting, said vertical web also being united to the diverging webs 30. Other bracing webs 34 may be provided between the rear end of the casing and the side walls, and still other webs 35 may be interposed between the side walls and horizontal web 31.

It will be perceived from my present invention that the metal is disposed in such a manner as to give maximum strength value to the several parts and also provide ample and readily accessible space for conveniently inserting and driving the rivets connecting the casting to the spaced car sills.

I claim:

1. A draft rigging back stop comprising side walls adapted to be secured to spaced car sills, a forward end wall united to said side walls and adapted to form an abutment for a movable part of the draft rigging, and transversely disposed rearwardly extending converging webs uniting the forward end wall to said side walls and forming a triangular reinforcing portion for said forward end wall.

2. A draft rigging back stop comprising side walls adapted to be secured to spaced car sills, a forward end wall united to said side walls and adapted to form an abutment for a movable part of the draft rigging, and a plurality of rearwardly extending converging webs united to said front end wall and to each other transversely of the back

3. A draft rigging back stop comprising side walls adapted to be secured to spaced car sills, a forward end wall united to said side walls and adapted to form an abutment for a movable part of the drawing rigging, and means including a plurality of transversely disposed webs arranged to form an angular reinforcement transversely adjacent said front end wall.

4. A draft rigging back stop comprising side walls adapted to be connected to spaced car sills, a forward end wall united to said side walls and adapted to form an abutment for a movable part of the draft rigging, and a longitudinally extending web uniting said side walls and having branches united at a plurality of spaced points to said front end wall.

5. A draft rigging back stop comprising side walls adapted to be connected to spaced car sills, a forward end wall united to said side walls and adapted to form an abutment for a movable part of the draft rigging, and a longitudinally extending substantially horizontal web uniting said side walls, said horizontal web having branches at its forward end united to said front end wall above and below a horizontal plane passing through said horizontal web.

6. A draft rigging back stop comprising side walls adapted to be connected to spaced car sills, a forward end wall united to said side walls and adapted to form an abutment for a movable part of the draft rigging, a longitudinally extending horizontal web uniting said side walls, a plurality of transversely extending webs uniting the front end wall and side walls, said webs forming a hollow column with said front end wall and a longitudinally extending vertical web uniting said horizontal web, transversely extending webs, and front end wall.

7. A draft rigging back stop comprising side walls adapted to be connected to spaced car sills, a forward end wall united to said side walls and adapted to form an abutment for a movable part of the draft rigging, and means including transversely disposed webs arranged to form with said front end wall a hollow column adapted to reinforce the same.

8. A draft rigging back stop comprising side walls adapted to be connected to spaced car sills, a forward end wall united to said side walls and adapted to form an abutment for a movable part of the draft rigging, and means including transversely arranged webs united to the front end wall near the upper and lower edges thereof, said webs being united to each other in spaced relation from said front end wall and forming therewith a transversely extending hollow column.

9. A draft rigging back stop comprising side walls adapted to be connected to spaced car sills, a forward end wall united to said

- side walls and adapted to form an abutment for a movable part of the draft rigging, and means including transversely disposed webs united to the front end wall in spaced relation, said webs being inclined with relation to the front end wall and united to each other in the rear of said front end wall to form a transversely extending hollow column.
10. A draft rigging back stop comprising side walls adapted to be connected to spaced car sills, a front end wall adapted to form an abutment for the movable element of the draft rigging, a floor web adapted to be secured to the bolster, a longitudinally disposed upright web extending rearwardly of the front end wall, and a longitudinally extending substantially horizontal web uniting the front end wall and said side walls, said horizontal web having openings therein upon either side of said upright web, said openings being in substantially vertical alignment with portions of said floor web.
15. A combined draft rigging back stop and center filler involving side walls having relatively high portions therein, said side walls being adapted to be connected to spaced car sills, a front end wall united to said side walls and forming an abutment for a movable element of the draft rigging, an upright wall extending from said front wall, a horizontal web uniting the side walls and said front end wall, a plurality of longitudinally arranged rivet openings in said side walls upon either side of the horizontal web, and additional rivet openings provided in said relatively high portions of said side walls.
20. A draft rigging back stop involving side walls adapted to be connected to spaced car sills, a front end wall adapted to form an abutment for a movable element of the draft rigging, and a hollow column reinforcing said front end wall, said column having its open ends terminating in said side walls near the forward end of said rivet openings.
25. A draft rigging back stop involving side walls adapted to be connected to spaced car sills, a front end wall forming an abutment for a movable part of the draft rigging, and transversely extending reinforcing webs uniting said side walls and front end wall, said webs being spaced from the front end wall and forming a triangular opening extending transversely of the casting.
30. A draft rigging back stop involving side walls adapted to be connected to spaced car sills, a front end wall adapted to form an abutment for a movable element of the draft rigging, and a chambered portion extending transversely of the casting adjacent the front end wall, said chambered portion being open through to the side walls.
35. In a draft rigging, the combination with spaced car sills, of a yoke slidably mounted therebetween, a casting connected to said sills and located in rear of said yoke, a buffing web extending transversely of said casting, a transversely disposed chambered portion adjacent said buffing web, said chambered portion opening against the car sills, and means for connecting the casting to said car sills.
12. A draft rigging back stop involving side walls adapted to be connected to spaced car sills, a plurality of rivet openings provided in said side walls, a front end wall uniting said walls and forming an abutment for a movable element of the draft rigging, and a hollow column reinforcing said front end wall, said column having its open ends terminating in said side walls near the forward end of said rivet openings.
13. A draft rigging back stop casting involving side walls adapted to be connected to spaced car sills, a front end wall forming an abutment for a movable part of the draft rigging, and transversely extending reinforcing webs uniting said side walls and front end wall, said webs being spaced from the front end wall and forming a triangular opening extending transversely of the casting.
14. A draft rigging back stop involving side walls adapted to be connected to spaced car sills, a front end wall adapted to form an abutment for a movable element of the draft rigging, and a chambered portion extending transversely of the casting adjacent the front end wall, said chambered portion being open through to the side walls.
15. In a draft rigging, the combination with spaced car sills, of a yoke slidably mounted therebetween, a casting connected to said sills and located in rear of said yoke, a buffing web extending transversely of said casting, a transversely disposed chambered portion adjacent said buffing web, said chambered portion opening against the car sills, and means for connecting the casting to said car sills.
- In testimony whereof I affix my signature.

DONALD S. BARROWS.
